FURNITURE PEDESTAL

Ronald H. Beckman, New York, N.Y., assignor to Herman Miller, Inc., Zeeland, Mich., a corporation of Michigan

Filed Nov. 27, 1964, Ser. No. 82,825

Term of patent 14 years

(Cl. D33—14)

FIG. 1.

FIG. 2.

FIG. 3.

FIG. 5.

FIG. 4.

FIG. 1 is a perspective view of the pedestal of the novel design;

FIG. 2 is an end elevational view of the pedestal;

FIG. 3 is a sectional view of the top portion of the pedestal taken on plane III-III of FIG. 2;

FIG. 4 is a sectional view of the top portion of the pedestal taken on plane IV-IV of FIG. 2; and

FIG. 5 is a sectional view of the support column of the pedestal, taken on plane V-V of FIG. 2.

The opposite end of the pedestal to that illustrated in FIG. 2 appears like the end illustrated in FIG. 2.

I claim:

The ornamental design for a furniture pedestal, substantially as shown and described.
